UNITED STATES PATENT OFFICE

AXEL GUSTAF EMANUEL HULTGREN, OF SODERFORS, SWEDEN

MACHINE FOR CENTERLESS GRINDING

Application filed June 8, 1927, Serial No. 197,443, and in Sweden February 24, 1926.

This invention relates to improvements in grinding machines and has for its object to provide an improved movable work support capable of automatically adjusting itself to the irregularities of the surface of the work.

In the accompanying drawing wherein the invention is illustrated:

Fig. 1 is a diagrammatic view of an arrangement of the regulating wheel, grinding wheel, stationary guide and the work piece.

Fig. 2 is a diagrammatic view of an approved embodiment of the invention.

Figs. 3a and 3b are similar views showing the use of the invention in the form of polygonal rollers.

Fig. 4 is a diagrammatic view of the invention illustrating the formation of a polygonal body having a greater number of faces than that of Figs. 3a and 3b.

Fig. 5 is a view similar to Fig. 2 showing a modification of the invention.

Fig. 6 shows a modification of the invention whereby bodies of tapering shape may be formed.

In so-called centerless grinding the object being ground is usually in contact with three bodies: the grinding wheel, a stationary guide and another rotating wheel. This wheel is often called the regulating wheel,

because it regulates the speed of rotation of the object. In Fig. 1 is shown a common arrangement of the object being ground 1, the regulating wheel 2, the grinding wheel 3 and the stationary guide 4. The point of contact,

of object 1, when viewed endwise with wheel 2 is not usually diametrically opposite to its point of contact with wheel 2 but displaced towards guide 4.

The aim of centerless grinding, as heretofore carried out is to shape the surface of the object into an accurate surface of rotation, usually a circular cylinder. This aim, however, has not always been achieved, inasmuch as the object, which is hereafter referred to as the roller, will sometimes assume in section, the shape of a rounded, regular polygon, usually having an odd number of faces, e. g. 3, 5 or 7. In consequence, for accurate work, finishing in a separate operation, by lapping, has become necessary.

The cause of this deviation from the round shape does not appear to be fully understood, nor is any method known of preventing it. Generally, the formation of a regular polygon in centerless grinding indicates, that the conditions are such as to permit the roller, although polygonal, to maintain continuous contact with the bodies 2, 3 and 4 in all positions during its revolution. Thus the polygonal shape, once formed, will be preserved in grinding down.

If the number of bodies in contact with the roller were increased, say, to four, the tendency for and chance of the formation of a polygonal shape would be lessened considerably or disappear, but, since a circle is already defined by three points on its periphery, the position of the fourth body, in order to ensure steady contact with the surface of the roller, would have to be adjusted, while the roller is being ground down, with such accuracy that this method cannot be realized in practice.

The difficulty described above is overcome according to the present invention, in its simplest form, by replacing the fixed guide 4 of Fig. 1 by the rocking or swinging guide 4 of Fig. 2. The rocking guide has, viewed endwise, two points of contact with the roller. The rocking axis, here shown as a knife-edge, is parallel to the axis of the roller. The two points of contact are on opposite sides of a plane through both axes, 2 is the regulating wheel, 3 the grinding wheel. It is clear that during grinding the rocking guide 4 automatically assumes such a position that both contact edges touch the roller in all positions of the latter. Thus continuous contact at four points of the periphery of the roller is ensured.

Grinding experiments on rollers, using the arrangement shown in Fig. 2, have proved that, starting with round rollers, round or polygonal rollers may be obtained depending upon conditions to be illustrated by the following example. In Figs. 3a and 3b is shown a case that actually occurred, where a round roller in grinding was gradually transformed into hexagonal shape with rounded sides. The grinding wheel 3 was steadily fed to

wards the wheel 2. During each revolution the roller 1 passed through a series of angular positions the extremes of which are shown in Figs. 3a and 3b, all other positions being intermediate between those two. The guide 5 4 rocked back and forth thus preserving contact with the roller in all positions at both edges. In Fig. 3a three adjacent corners of the hexagon are shown touching the regulating wheel 2 and the two contact edges of guide 4 respectively, while one of its sides touches the grinding wheel. In Fig. 3b conditions are reversed.

By accurate measurement was determined 10 that, in order to produce the hexagonal shape the following condition must be approximately fulfilled:

$$\alpha : \beta : \gamma : \delta = 1\frac{1}{2} : 1 : 1 : 2\frac{1}{2}$$

20 where α, β, γ and δ are the center angles shown in Fig. 3a. In another test the same result was obtained when the values of α and γ were reversed. By modifying the relative position of the bodies 2, 3 and 4 regular polygons with 25 4, 6, 7, 8, 10, 12, 14, 15, 16, 17, 18, 19, 22, 25 and more sides were obtained.

From the experiments made a general law was deduced for the formation of regular 30 polygonal shape when using a rocking member or guide in centerless grinding. This law is expressed in the following equations:

$$\alpha : \beta : \gamma : \delta = m : n : (p + \frac{1}{2}) : (q - \frac{1}{2})$$

35 or alternately

$$\alpha : \beta : \gamma : \delta = (m + \frac{1}{2}) : n : p : (q - \frac{1}{2})$$

$$\alpha + \beta + \gamma + \delta = 360^\circ$$

$$N = m + n + p + q$$

40 where m, n, p , and q are integral numbers and α is the number of sides of the resulting polygon.

As an example, a regular polygonal shape 45 with 17 sides may be obtained by making

$$\alpha : \beta : \gamma : \delta = 74^\circ, 1:84^\circ, 7:63^\circ, 5:137^\circ, \\ 6=3, 5:4:3:6, 5.$$

This case is illustrated in Fig. 4.

50 The conditions for obtaining accurately circular shape, when using a rocking guide in centerless grinding will now be considered. If, after a certain polygon has formed, the grinding is continued, by feeding the grinding wheel towards the regulating wheel, the diameter of the roller decreases and the angles α, β, γ and δ slowly change their values until, at a given instance, a tendency for another polygon to form will develop. In the 55 transition stage the roller will usually be accurately circular. That stage may, however, be difficult to catch in practice.

A provision that has the advantage of permitting fairly wide variation in the diameter 60 of the roller, consists in making α equal to γ ,

in other words, in placing the rocking guide centrally between the contacts of the rollers with the two wheels. As already demonstrated, for any polygonal shape to form, one of the following equations should be satisfied: 70

$$\alpha : \gamma = m : (p + \frac{1}{2})$$

or

$$\alpha : \gamma = (m + \frac{1}{2}) : p$$

75

where m and p are integral numbers. Obviously then, since $\alpha = \gamma$, no polygon may be formed and the roller must become circular or, if already circular, must remain so, as long as $\alpha = \gamma$. Experiments have confirmed 80 this conclusion.

The degree of roundness attainable by using the method now described may be estimated by the following example. We assume an error of 1% in adjusting $\alpha = \gamma$. Hence 85

$$\alpha : \gamma = 100 : 101 = 50 : (50 + \frac{1}{2}) = m : (p + \frac{1}{2}).$$

If, further, the angles β and δ are of the same order of magnitude as α and γ , it follows that: 90

$$\alpha : \beta : \gamma : \delta = 50 : 50 : 50, 5 : 49, 5 =$$

$$m : n : (p + \frac{1}{2}) : q - \frac{1}{2}$$

and $N = 50 + 50 + 50 + 50 = 200$. A polygon having 200 sides may, therefore, form. Generally, the number of sides of the polygon possible will be inversely proportionate to the error of adjustment.

When this method is carried out in practice, it is found that an approximate adjustment only is needed to produce perfect roundness. This is no doubt due to the fact that when polygons with many sides only are possible, the grinding will continuously alter the relation between the angles to suit new polygons, in other words no particular polygon will have time enough to establish itself and perfect roundness results. 105

It is not necessary that the roller glides over both contact edges of the rocking guide. One or both of these edges may be substituted by rolls, either driven or idle, mounted on the guide. In order to drive and regulate the speed of rotation of the roller it is only necessary that one of the rolls or wheels present, not counting the grinding wheel, is driven. In case a regulating wheel is mounted on the rocking device, a stationary guide may take the place of the wheel 2 of Fig. 2. Also two rocking devices may be used.

In some cases it may be of advantage to mount one or two rocking guides on one or both limbs of a larger rocking device as shown schematically in Fig. 5. By thus increasing the number of effective contacts the chances for polygonal shape to form are further minimized.

If the axis of the rocking member or guide and the axes of the grinding and regulating wheels are made to converge into one point,

conical or pyramidal objects may be ground, depending upon the adjustment of the contact angles. An axial support at the large end of the object is then added to receive the thrust.

5 For the knife-edge of the rocking guide may be substituted two journals moving in bearings or a cylindrical bottom surface resting on a cylindrical groove of larger radius of curvature. In the latter case the rocking action is effected by rolling of the one cylindrical surface upon the other.

10 The description given above applies when the object being ground is not moved axially in grinding. For continuous grinding of cylindrical or prismatic objects that are fed axially through the machine the devices described may also be employed with the modifications continued by the inclined positions 20 of the axes of the grinding and regulating wheels to each other.

Having now described my invention, what I claim as new and desire to secure by Letters Patent is:

25 1. In a machine for centerless grinding of surfaces of revolution or regular polygonal surfaces, a grinding wheel and work supporting members, one of said members being constituted by a rotating wheel, at least one of 30 said members being mounted to freely rock on a rigid support, the axis of the work being substantially parallel to the axis of the rocking movement of the last mentioned member, the latter being provided at each side of 35 a plane determined by the two axes mentioned with a work engaging surface.

40 2. In a machine for centerless grinding of surfaces of revolution or regular polygonal surfaces, a grinding wheel and work supporting members, one of said members being constituted by a rotating wheel, at least one of 45 said members being mounted to freely rock on a rigid support, the axis of the work being substantially parallel to the axis of the rocking movement of the last mentioned member, the latter being provided at each side of a plane determined by the two axes mentioned with work engaging portions, said work engaging portions being constituted by rock- 50 able members movable about axes parallel to the first mentioned rocking axis.

45 3. In a machine for centerless grinding of conical or regular pyramidal surfaces, a grinding wheel and work supporting members, one of said members being constituted by a rotating wheel, at least one of said members being mounted to freely rock on a rigid support, the axis of the work substantially intersecting the axis of the rocking movement 55 of the last mentioned member, the latter being provided at each side of a plane determined by the two axes mentioned with a work engaging surface.

60 4. In a machine for centerless grinding of surfaces of revolution, a grinding wheel and

work supporting members, one of said members being constituted by a rotating wheel, serving as driving or regulating wheel, at least one of said members being mounted to freely rock on a stationary support, the axis of the work being situated in the same plane as the axis of the rocking movement of the last mentioned member, the latter being provided at each side of said plane determined by the two axes mentioned with a work engaging surface, the rocking member being so disposed in relation to the grinding wheel and the regulating wheel that the distance from one work engaging surface of said rocking member to the work engaging surface of the grinding wheel is substantially equal to the distance from the other work engaging surface of the rocking member to the work engaging surface of the regulating wheel.

65 5. In a machine for centerless grinding of regular polygonal surfaces, a grinding wheel and work supporting members, one of said members being constituted by a rotating wheel, serving as driving or regulating wheel, at least one of said members being mounted to freely rock on a stationary support, being situated in the same plane as the axis of the rocking movement of the last mentioned member, the latter being provided at each side of said plane determined by the two axes mentioned with a work engaging surface, the rocking member being so disposed in relation to the grinding wheel and the regulating wheel that a polygonal piece of work 70 of the desired size and shape when suitably placed in the machine will engage simultaneously one of said two wheels and the two said work engaging surfaces of the rocking member at each of three polygonal edges and the other of said wheels at one of its polygonal sides.

In witness whereof, I have hereunto signed my name.

AXEL GUSTAF EMANUEL HULTGREN.
